ALIGNING INSTRUMENT FOR PRINTING
STRUCTURES

Ernst Christen, Kriens, Switzerland

Application August 14, 1947, Serial No. 768,585
In Switzerland November 13, 1946

7 Claims. (Cl. 33—76)

1

This invention relates to setting and aligning of printing structures removably set and fastened in such manner as to produce best results as to the appearance of the printed matter, and particularly to an instrument for this purpose.

The main object of the present invention is to provide an instrument comprising a horizontal and vertical leg in adjustable T-shaped relation with scales attached thereto including setting members for minute positioning of printing structures mountable on a guide member, comprising a double armed indicator resiliently clamped to a guide member.

Other objects and advantages will be apparent from the following description when read in connection with the accompanying drawing in which:

Figure 1 is a front view of the aligning instrument.

Figure 2 is a cross-section of the aligning instrument.

Figure 3 is a top plan view of the instrument, Figures 4 and 5 are details.

Referring to the drawing, reference numeral 1 designates a guide member provided with a longitudinal slot 2, mounting screws 3 on a pair of supports 4 being provided to fix the instrument for suitable positioning of the printing structure. Screws 5 are provided to fix the instrument to a frame. The guide member 1 supports an elongated band 50 having scales 6, 7 formed thereon, the band 50 being fixed to the guide member 1 by any suitable structure. For example, and as clearly shown in Fig. 3, the band 50 may be secured in place on the guide member 1 by mechanism 8 in cooperation with the upstanding pins 51 carried by guide member 1. The pins 51 project through suitable openings in the band 50 and restrain one end of the band 50 while the mechanism 8 restrains and tensions the other end of the band. Mechanism 8 includes a plate 52 slidable within the longitudinally extending dove-tail slot 53, the plate carrying upstanding pins 54 which project through suitable openings provided in the adjacent end of band 50. It is apparent that movement of the plate 52 and pins 54 away from fixed pins 51 will rigidly clamp the elongated band 50 in place on the guide member 1. Accordingly, a threaded actuating member 55 is rotatably connected to the plate 52 and is supported in a complementary sleeve 56 carried by the guide member 1 for moving the plate 52 toward and away from the fixed pins 51. Movement of the plate 52 toward the pins 51 will permit the band 50 to be removed, and movement of the plate 52 away from the pins

2

51 will clamp the band 50 in place. Slidably supported in the longitudinal T-slot 2 is a glide 9 including a measuring leg 10 arranged at right angles to the guide member 1. The instrument further includes a plate secured to the glide 9 and provided with openings 11, 12 cooperating with the scales 6, 7 of band 50. Another elongated band 57 having scales 13, 14 thereon is mounted on leg 10 by any suitable structure 15, as for example, the arrangement for band 50. Since various mountings constructed and arranged in accordance with principles and practices well understood, may be used, a detailed description of a specific mounting is dispensed with as superfluous.

Spring pressed bolts 16 comprising lateral noses 17 disposed in the glide 9 engage the edge of the longitudinal slot 2. The resilient mounted bolt 16 comprises a knob 18 to rotate therewith the lateral nose 17. The spring-bolt 16 is arranged to screw-threadedly engage an operating disk 19 which surrounds the knob 18 (see Figure 5). Accordingly, upon rotation of the operating disk 19, the bolt may be displaced upwardly or downwardly. The spring 20 is circumposed about the bolt 16 and is flexed against the shoulder 21 in the glide 9 and also against the operating disk 19. 22, 23 represent an arresting arrangement positively preventing rotation of bolt 16 and its nose 17 after the glide 9 has been slidably secured in T slot 2 with nose 17 pressing against the upper surface of said slot under pressure of spring 20, this arrangement comprising a fixed pin 22 in the bolt 16 and a slot 23 on the underside of the glide 9. The arresting arrangement is such that when the lateral nose 17 engages behind the edge of the longitudinal slot 2, thereafter in response to rotation of the disk 19 and upward displacement of bolt 16, glide 9 is in the locked position. In the zone of desired relative sliding between the glide 9 and the measuring leg 10 a toothed rack bar 24 is disposed (see Figures 4 and 5). The glide 9 carries a bolt 25 supporting a gear 26 adapted to engage rack 24. The bolt 25 comprises on the upper side of the glide 9 an operating disk 27 (Figure 4) and said bolt is maintained against accidental rotation by means of a spring 28 bearing upon a collar 29 of bolt 25, which collar rests on shoulder 30 of the glide 9; spring 28 also rests upon a nut 31 threadedly engaged in said glide. Bolt 25 extends through nut 31 so that the bolt is free of the nut 31 and may be intentionally rotated by disk 27 to turn gear 26 and hence to move glide 9 along guide 1. The measuring leg 10 comprises a head 32 and

a double armed indicator 33. The double armed indicator or aligner 33 comprises securely fastened thereto indicators 34 cooperating with the scales 13, 14 of the band 57. Resilient clamping means provide for positioning of the two arm indicators. The resilient clamping means comprise on either side of the measuring scale 10 a sleeve 35 fixedly seated in a head piece 32. Each sleeve 35 contains a spring 36. The spring 36 is located between a nut 38 (having a flange 37) and a collar 39 fixed to a bolt 40. The bolt 40 comprises also, for pulling purposes, a knob 41. The bolt 40 therefore presses on the plate 42 and the latter in turn upon the side wall of the frame type measuring leg. A support 43 near the free end of the measuring leg 10 engages by a dove-tail the underside of the measuring leg and is slidably thereon but arranged to be set fast on the measuring leg by means of the screw 44.

Depending from support 43 are legs 46 which are adjustably fastened to the support 43, by means of screws 45. These legs rotatably support rollers 47 which may be adjustable in height relative to the translatable leg 10 by changing the angular position of the respective legs 46. The disclosed construction of the instrument functions as follows:

When the part containing the printing structure has been positioned outside the machine, the supports 4 are fastened at a suitable position to the main frame, accurately engaging the positioning plate thereby providing the device with a good guiding support. By means of the screws 5 the supports 4 are fastened to the frame (shown in Figure 1). Then the guide-member 1 is brought into engagement with the supports 4 in such manner that the center thereof is positioned directly over the middle frame member of the positioning frame. The guide-member is then firmly secured in place on supports 4 by means of screws 3. Then the measuring leg 10 including the glide 9 is set into the longitudinal slot 2 of the guide-member 1 in such manner that the lateral noses 17 are capable of engaging the longitudinal slot 2 and the pins 22 of the arresting or locking devices received within slots 23. In operation the gear 26 is brought into the plane of the toothed bar 24, thereby engaging it. When the initial position of the gear 26 is such that the teeth thereof bear against the side-walls of the toothed bar 24, the setting of the glide 9 into the guide member 1 is not hindered, because the gear 26 including the bolt 25 and the operating disk 27 are resiliently mounted and may be displaced upwardly. When the glide 9 is set in the guide-member 1 the resiliently supported bolts 16 are rotated by means of the knobs 18, whereby the lateral noses 17 engage the edge of the longitudinal slot 2, and also registering the pins 22 and the slots 23.

By this arrangement the measuring leg 10 supported at its free end by the rollers 47 is capable of moving on the foundation, thereby capable of controlling parallelism of the sides of printing structures due to the scales provided for this purpose. Engagement of the operating mechanism for the glide 9 may be accomplished by means of a slight rotation of the gear 26 by means of the operating disk 27. This will only be necessary if the gear 26 is not initially in meshed relation with the toothed bar 24. By means of the operating disk 27 the measuring leg 10 is capable of being minutely set in relation to the guide member 1. The measuring leg 10 may be

fixed in an adjusted position by rotation of the operating disk 19 to displace the bolt 16 upwardly, whereby the spring 20 is tensioned, thereby pressing the lateral noses 17 against the edge of the longitudinal slot 2, whereby the measuring leg 10 is firmly fixed upon the guide-member 1. The two indicators 34 may be moved in opposite directions as a unit on the measuring leg 10, whereby control of registered condition is made possible in that the plates 42 are slidably moved on the measuring leg 10.

The clamping effect of the plates 42 is controlled by displacement of the screw-nuts 38 and the displacement of the double armed indicator 33 on the measuring leg 10 is facilitated by the pull buttons 41. The clamping effect relating to the double armed indicator on the measuring leg 10 may be increased by tightening the screw nuts 38. The displaceable and lockable movement of the measuring leg 10 on the guide-member 1 enables quick positioning on the guide-member 1 by gliding.

Smooth gliding adjustment of the double armed indicator 33 is assured by varying the clamping effect, which accounts also for the desired fixation of the double armed indicator 33 on the measuring leg 10. An accurate adjustment in height above the printing structure of the measuring leg is made possible by the supporting rollers 47 at the free end of the measuring leg 10.

It is claimed and desired to secure by Letters Patent:

1. An aligning instrument for printing structures comprising, a guide member having a longitudinal slot therein, means for securing said guide member to the top of a frame, a translatable leg positioned substantially at right angles to said guide member and having a glide portion adjacent one end and slidably received in the longitudinal slot in said guide member, spring pressed bolts on said glide portion and each having a lateral nose for clamping engagement with a wall of said longitudinal slot, means for adjusting the clamping pressure of said bolts, gear means including cooperating elements carried by said guide member and said glide portion for adjusting the position of the latter along said guide member, rollers supporting the other end of said translatable leg, a double armed indicator slidable on said translatable leg, and means for resiliently clamping said indicator in position on said translatable leg.

2. An aligning instrument for printing structures comprising a guide member having a longitudinal slot therein, means for securing said guide member to the top of a frame, a translatable leg having a free end and positioned substantially at right angles to said guide member and having a glide portion slidably received in the longitudinal slot in said guide member, spring pressed bolts on said glide portion and each having a lateral nose for clamping engagement with a wall of said longitudinal slot, means including a knob attached to each bolt for rotating the same to permit withdrawal of said nose from said slot, means for adjusting the clamping pressure of said bolts, gear means including cooperating elements carried by said guide member and said glide portion for adjusting the position of the latter along said guide member, rollers supporting said free end of said translatable leg, a double armed indicator slidable on said translatable leg, and means for resiliently clamping said indicator in position on said translatable leg.

3. An aligning instrument for printing structures comprising a guide member having a longitudinal slot therein, means for securing said guide member to the top of a frame, a translatable leg having a free end and positioned substantially at right angles to said guide member and having a glide portion slidably received in the longitudinal slot in said guide member, spring pressed bolts on said glide portion and each having a lateral nose for clamping engagement with a wall of said longitudinal slot, means for adjusting the clamping pressure of said bolts, means carried by said bolts and engageable with said glide portion for preventing rotation of said bolts, gear means including cooperating elements carried by said guide member and said glide portion for adjusting the position of the latter along said guide member, rollers supporting said free end of said translatable leg, an indicator, and means for mounting and resiliently clamping said indicator in position on said translatable leg.

4. An aligning instrument for printing structures comprising a guide member having a longitudinal slot therein, means for securing said guide member to the top of a frame, a translatable leg having a free end and positioned substantially at right angles to said guide member and having a glide portion slidably received in the longitudinal slot in said guide member, spring pressed bolts on said glide portion each having a lateral nose for clamping engagement with a wall of said longitudinal slot, means for adjusting the clamping pressure of said bolts, means including a pin on each of said bolts engageable with respective slots in said glide portion for preventing rotation of said bolts, gear means including cooperating elements carried by said guide member and said glide portion for adjusting the position of the latter along said guide member, rollers supporting said free end of said translatable leg, an indicator, and means for mounting and resiliently clamping said indicator in position on said translatable leg.

5. An aligning instrument for printing structures comprising a guide member having a longitudinal slot therein, means for securing said guide member to the top of a frame, a translatable leg having a free end and positioned substantially at right angles to said guide member and including a glide portion slidably received in said longitudinal slot, spring pressed bolts on said glide portion and each having a lateral nose for clamping engagement with a wall of said longitudinal slot, means for adjusting the clamping pressure of said bolts, gear means including a rack mounted along the longitudinal slot in said guide member, a pinion rotatably mounted on said glide portion and in engagement with said rack for adjusting the position of said translatable leg along said guide member, rollers supporting said free end of said leg, a double armed indicator slideable on said translatable leg, and means for resiliently clamping said indicator in position on said translatable leg.

6. An aligning instrument for printing structures comprising a guide member having a longitudinal slot therein, means for securing said guide member to the top of a frame, a translatable leg having a free end and positioned substantially at right angles to said guide member and having a glide portion slidably received in the longitudinal slot in said guide member, spring pressed bolts on said glide portion and each having a lateral nose for clamping engagement with a wall of said longitudinal slot, means for adjusting the clamping pressure of said bolts, gear means including cooperating elements carried by said guide member and said glide portion for adjusting the position of the latter along said guide member, rollers supporting said free end of said leg, a double armed indicator slideable on said translatable leg, resilient clamping means on said indicator comprising at least one pull button movable under spring pressure to clamp against said leg, and means for adjusting the clamping pressure on said pull button.

7. An aligning instrument for printing structures comprising a guide member having a longitudinal slot therein, means for securing said guide member to the top of a frame, a translatable leg positioned substantially at right angles to said guide member and having a glide portion on one end thereof slidably received in the longitudinal slot in said guide member, spring pressure bolts on said glide portion each having a lateral nose for clamping engagement with a wall of said longitudinal slot, means for adjusting the clamping pressure of said bolts, gear means including cooperating elements carried by said guide member and said glide portion for adjusting the position of the latter along said guide member, rollers supporting the other end of said translatable leg, means for adjusting the height of said rollers relative to said leg, a double armed indicator slideable on said translatable leg, and means for resiliently clamping said indicator in position on said translatable leg.
